STRIP FEEDING DEVICE

John T. Davidson, Dayton, Ohio, assignor to The Standard Register Company, Dayton, Ohio, a corporation of Ohio

Application January 21, 1954, Serial No. 405,386

11 Claims. (Cl. 271—2.4)

This invention relates to strip feeding apparatus and methods, and more particularly to such apparatus and methods achieving a compound motion of the strip.

While not so limited, the invention is well adapted for use with addressograph machines and the like, wherein a strip of series connected detachable record forms are fed to and from an imprinting station.

The object of the invention is to improve the construction as well as the means and mode of operation of strip feeding devices, whereby such devices may not only be economically manufactured, but will be strong and sturdy in construction, of relatively compact nature, adaptable to a wide range of usage, but having relatively few parts and be unlikely to get out of repair.

It is an object of the invention to enable plural column listing upon a single record form.

A further object of the invention is to provide for motion of the record strip in a lateral as well as a longitudinal sense.

Another object of the invention is to introduce a principle of dual feed in machines of the kind described wherein different parts of a manifold strip assembly may be advanced different amounts, making it possible, for example, to make efficient use of a summary record strip.

A further object of the invention is to achieve in a machine of the kind described a compound motion of the strip involving a differential advance of different parts of the strip in a longitudinal sense plus lateral columnar adjustment of the strip assembly as a unit.

Still another object of the invention is to provide for columnar adjustment of the strip automatically and as a part of the machine operation.

A still further object of the invention is to present dual feed mechanisms independently operable as a part of the machine operation.

Still another object of the invention is to introduce a new method of strip feeding, substantially as herein disclosed.

A further object of the invention is to provide a strip feeding device possessing the advantageous structural features, the inherent meritorious characteristics and the mode of operation herein disclosed.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

Referring to the accompanying drawings, wherein is shown one but obviously not necessarily the only form of embodiment of the invention,

2

Fig. 1 is a view in perspective of an addressograph machine, having strip feeding apparatus in accordance with the instant invention installed thereon;

Fig. 2 is a plan view of the strip feeding apparatus, some parts thereof being omitted;

Fig. 3 is a view of the strip feeding apparatus in rear end elevation;

Fig. 4 is a view of the strip feeding apparatus in side elevation;

Fig. 5 is a view in longitudinal section, taken substantially along the lines 5—5 of Fig. 2, some parts being omitted;

Fig. 6 is a plan view of the rear portion of the strip feeding apparatus, with some parts removed for a better showing of the feeding mechanism;

Fig. 7 is a view in longitudinal section, taken substantially along the lines 7—7 of Fig. 6;

Fig. 8 is a detail view, partly in cross section, of the variable mechanism for operating the feeding devices at the front of the machine;

Fig. 9 is a fragmentary view, in longitudinal section, taken substantially along the lines 9—9 of Fig. 2;

Fig. 10 is a view similar to Fig. 9, taken substantially along the lines 10—10 of Fig. 2;

Fig. 11 is a detail view, in side elevation, of certain operating controls;

Fig. 12 is a fragmentary view in cross section, taken substantially along the line 12—12 of Fig. 7;

Fig. 13 is a wiring diagram indicating the relationship of the power source and operating controls in the machine; and

Fig. 14 is a view in perspective of the mechanism for effecting lateral shifting of the feeding devices.

Like parts are indicated by similar characters of reference throughout the several views.

In the illustrated instance, the strip feeding apparatus and method of the present invention are disclosed as an attachment of an addressograph machine. The feeding apparatus is operable upon a manifold strip assembly made up of a part 20 and another part 21 (Fig. 1). In the present strip assembly, the part 20 thereof includes series connected check forms 22, with offset stub portions 23, and further includes a strip 24 of transfer material and another set of series connected record forms 25, which may, for example, be Federal Income Tax Withholding Statements.

The part 21 of the strip assembly is narrower than the part 20 and is made up of a transfer strip 26 and a journal or summary strip 27.

The strip feeding apparatus is installed as super structure on the addressograph machine which provides a support therefor in the form of a table 28. As seen also in Fig. 4, brackets 29 are mounted on the table 28 and support a pack holder device 31 having separate compartments for respective supply packs, in which the parts 20 and 21 are placed in the machine for feeding. The free ends of the parts 20 and 21 of the strip assembly project out of the holder 31 toward what may be considered the front of the machine, or the left hand end thereof as viewed in Fig. 4. Beyond the holder 31, the separate parts of the strip achieve a superposed, adjacent relation, resting on a bridge-like member 32. The member 32 inclines downwardly toward the table 28, and, at the lower end thereof, the strip assembly separates again into its component parts, passing over respective feeding devices 41 and 38. The strip material comprising the manifold strip assembly is marginally perforated, and the feed-

ing devices 41 and 38 include pin wheels which engage the marginal perforations in the strips for positive feeding thereof and for the maintaining of accurate registration.

Beyond the feeding devices 41 and 38 the strip assembly resumes its unitary form and passes in a generally reverse direction over the table 28 toward the rear of the machine, or the right hand end thereof as viewed in Fig. 4. About mid way of its travel over the table 28, the strip assembly passes through the addressograph imprinting station, indicated diagrammatically herein at 37. As will be described, by intermittent feeding increments imparted to the strip assembly, successive record forms are brought to the imprinting station, are there imprinted upon, and then are moved on for separation or for refolding. Toward the end of the table 28, the strip assembly again is separated into its parts 20 and 21, the part 20 passing over a feeding device 34 and being directed thereby into a refold compartment 39, and the part 21 passing over a feeding device 33 and being directed thereby into a refold compartment 42.

It may thus be considered that there is associated with the strip part 20 a front feeding device 41 and a rear feeding device 34 and that there is associated with the strip part 21 a front feeding device 38 and a rear feeding device 33. The separate strip parts 20 and 21 may thus be advanced independently of one another or in unison and they may, moreover, be advanced differentially, that is, in increments or steps of differing lengths.

Considering the feeding devices 33 and 34 and 38 and 41 in greater detail, and referring to Fig. 6, the rear devices 33 and 34 respectively include transverse shafts 43 and 44. On the shaft 43 pin wheels 35 are detachably secured in spaced apart relation with strip supporting discs 45 therebetween. The shaft 44 has pin wheels 36 detachably secured thereto and in a spaced relation different from that of the wheels 35, supporting discs 46 like the discs 45 being mounted on the shaft 44 between the pin wheels 36.

The front feeding device 38 (Fig. 2) includes a pair of pin wheels 47 complementary to the pin wheels 35, detachably secured on a shaft 48. The feeding device 41 includes pin wheels 49, complementary to the pin wheels 36, and detachably secured to a shaft 51. The pin wheels 47 and the pin wheels 49 are respectively surmounted by paper or strip guides 52 and 53.

Referring to Fig. 4, forwardly projecting brackets 54, attached to the addressograph machine, support a transverse frame member 55 which provides a mounting for the front pin wheel shafts 48 and 51. The rear shafts 43 and 44 have their one ends received in respective bearings 56 and 57 in a frame supported bracket 58, while the opposite end of the shafts 43 and 44 are received in respective frame supported bearings 59 and 61.

With respect to the front feeding devices 38 and 41, these are mounted in a projecting frame 62 fastened to the member 55. Frame supported bearing housings 63 and 64 receive the opposite ends of the pin wheel shafts 48 and 51, the housing member 63 containing bearings 65 and 66 corresponding to the above mentioned bearings 59 and 61, and shown in Fig. 8, and the housing member 64 containing bearing elements (not shown) corresponding to the bearings 56 and 57 aforementioned. The bearing elements 56 and 57 and the corresponding bearing element in the housing member 64 are of identical construction. Thus, as seen in Figs. 6 and 7, the bearings are cylindrical and include needle bearings 67 and ball bushings 68. The several shafts have a direct mounting in the bearings 67 and 68 and project through and beyond such bearings into respective air cylinders or dash pots 69.

The several bearings 59, 61, 65 and 66 also are identical and are generally the same as the bearings 56 and 57. Thus, as shown in Fig. 8, the bearing 66 includes needle bearings 70 and a ball bushing 71. In this instance,

however, there is interposed between the needle bearing 70 and the ball bushing 71 one end of a sleeve 72. The other end of the sleeve 72 is pinned to a shaft 73. The shaft 73 projects out of the sleeve 72 and is received in a bushing 74 with the outer ends of the shaft 73 and bushing 74 being interconnected through a variable member 75. A frame supported bearing 76 is aligned with the bearing 66 and cooperates therewith in supporting the assembly comprising the sleeve 72, shaft 73 and sleeve 74 for rotary motion relatively to the frame 62.

The shaft 51 extends through and beyond the bearing 66 into the sleeve 72 where a key 77 thereon is slidably received in a groove 78 in the sleeve. The shaft 51 accordingly is connected to the sleeve 72 for unison rotary but relative axial motion.

A sleeve 79 is similarly installed between the bearing 65 and a frame mounted bearing 81. The shaft 48 is received in and connected to the sleeve 79 in the same manner that the shaft 51 is received in and connected to the sleeve 72. Further, the sleeve 79 is connected to a shaft 82 and the latter is engaged with a sleeve 83 through a variable 84, all in the same manner as described above with respect to sleeve 72 and its associated parts.

The opposite ends of the shafts 51 and 48 extend through the bearing housing 64 into another housing 85 containing dash pot air cylinders corresponding to the cylinders 69 of Fig. 6. The variables 75 and 84 are not disclosed in detail herein, it being understood that these devices perform a known function in permitting the shafts 48 and 51 to be rotatively adjusted manually, independently of such rotary driving mechanism as may be provided therefor.

The bearings 59 and 61, associated with the left hand end of the shafts 43 and 44, as viewed in Fig. 6, are as before described like the bearings 65 and 66. There is, moreover, a sleeve 86 associated with the bearing 59 and a sleeve 87 associated with the bearing 61 corresponding to the sleeves 72 and 79. The sleeves 86 and 87 receive the respective shafts 43 and 44 for unison rotary and relative axial motion, also in the same manner that the shafts 48 and 51 are received in the sleeves 72 and 79. Further, the sleeves 86 and 87 are similarly mounted and actuated. Referring to Fig. 12, where sleeve 86 is shown by way of example, the outer end thereof is pinned to a stub shaft 88 which extends through a bushing 89 installed in a frame mounted bearing 91. The outer end of the shaft 88 and of the bushing 89 are interconnected by a tube 92 forming part of a variable like the variables 84 and 75 previously described. The bushing 89 is formed with a gear 93, serving a purpose hereinafter to be described.

The shaft 43 and the shaft 48 are interconnected for unison rotary motion, and the shafts 44 and 51 are similarly interconnected. Thus, the aforementioned gear 93 meshes with a gear 94 (Fig. 7) mounted in a frame supported bearing 95, and the corresponding gear (not shown) associated with sleeve 87 meshes with a gear 96 in a frame supported bearing 97. The gear 94 is on a shaft 98, also carrying a mitre gear 99. The gear 99 meshes with a similar gear 101 on a shaft 102, such shaft extending alongside the strip feeding apparatus and having a bearing in housings 103. The gear 96 is on a shaft 104, also carrying a mitre gear 105. The gear 105 meshes with a similar gear 106 on a shaft 107 which extends in parallel relation to the shaft 102 and is similarly supported.

The shafts 102 and 107 extend toward the front of the machine and have their ends received in respective bearing housings 108 and 109. Extending through and beyond housing 108, the shaft 102 has a mitre gear 110 thereon meshing with a similar gear 111 on the bushing 83. Similarly the shaft 107 extends through housing 108 and an offset extension 107a thereof is geared to a mitre gear 112 meshing with a like gear 113 on the bushing 74. According to the construction and arrangement

of parts, therefore, rotation of the gear 93 (Fig. 12) will effect a corresponding and simultaneous rotation of the shaft 43 of feeding device 33 and of shaft 48 of feeding device 38. Also, rotation of the gear corresponding to gear 93, and associated with sleeve 87, will result in a corresponding and simultaneous rotation of the shaft 44 of feeding device 34 and shaft 51 of feeding device 41.

The actuation of such gears is effected by individual motorized units contained in respective housings 114 and 115 (Fig. 2), with the unit of housing 114 being shown in some detail in Fig. 7. The construction and mode of operation of the motorized units is substantially the same as those disclosed in Davidson et al. application, Serial No. 62,798, filed December 1, 1948, now Patent No. 2,700,334, for Strip Feeding Device. Such mechanism will accordingly be only briefly described herein. Thus, and referring to the unit shown in Fig. 7 as operative upon gear 93, the gear 93 meshes with a gear 116 on a shaft 117 in the housing 114. Also on the shaft 117 is a gear 118 meshing with a large gear 119 on a housing supported shaft 121. The shaft 121 extends through the housing 114 into driven relationship with a motor 122. Also on the shaft 121 is a disc 123, sometimes called a program disc, the circumferential spacing of notches 124 on its periphery determining the length of successive steps of advancement of the record strips.

In the operation of the machine, the direction of rotation of the motor 122 is clockwise as viewed in Fig. 7. Rotation of the disc 123 in this direction normally is prevented by a pawl 125 which engages one of the teeth 124 of the disc 123. The pawl 125 is released or disabled by a finger 126 on a lever 127, the movement of which is controlled by an electromagnetic device 128. Energizing of the device 128 results in a counter clockwise rocking motion of the lever 127 and a releasing of the pawl 125. In moving to releasing position, the pawl 125 rocks in a clockwise direction and acts upon a plunger 129 of a switch 131 which is in a circuit with the motor 122. Thus the release of the pawl 125 serves also to initiate operation of the motor 122 so that as substantially concomitant operations the pawl 125 is moved out of engagement with a tooth 124 and the motor 122 is energized to rotate shaft 121 and associated parts leading to gear 93 and gear 94. The energizing of the electromagnet 128 may be of momentary duration, and, once released, the pawl 125 is free to return to contact with the periphery of the disc 123 and will reengage the first encountered notch 124 thereon thus interrupting the feeding operation.

It will be understood that the motorized device above described is effective upon the feeding devices 33 and 38, and that another and substantially identical motorized device is provided for operating the feeding devices 34 and 41. The second said device, as noted, is contained in housing 115 and is made up of parts like those above described, including a separate and individual motor 132 (Fig. 2). Referring to Fig. 13 of the drawings, the electromagnet 128 of the motorized units, the switches 131 thereof and the motors 122 and 132 are connected in an electrical circuit 133 controlled by a switch 134. Thus, when the switch 134 is closed the electromagnets 128 are energized and a strip feeding operation ensues as above described. When the switch 134 opens, the electromagnets 128 are deenergized and the strip feeding operation is interrupted, as the pawls 125 return to normal positions on the periphery of the respective discs 123. Also included in each motorized unit, and indicated generally in Fig. 13 at 135, is a delay means operable to hold the switch 131 closed until the disc 123 has advanced at least the distance of one notch.

The switch 134 is shown in Fig. 11 as operated by a cam 136 mounted on a shaft 137 and having a single actuating formation 138 on its periphery. Considering the switch 134 to be normally open, the illustrated construction and arrangement of parts is such as to cause the

switch 134 momentarily to close once for each revolution of the shaft 137. The latter is mounted in a frame member 139 and carries a gear 141 meshing with a gear 142 on a shaft 143. The shaft 143 is the principal clutch shaft 5 of the addressograph machine. For each revolution thereof of the machine completes a cycle of operation, including an actuation of the imprinting mechanism. The gear 141 is approximately twice as large as the gear 142. Thus, since two complete revolutions of the shaft 143 and gear 10 142 will be required to effect one complete revolution of the shaft 137 and gear 141, it will be understood that the switch 134 is closed once for each two revolutions of the clutch shaft 143. This means, therefore, that feeding of the record strips in the instant illustrated embodiment of 15 the invention is accomplished on every other or alternate imprinting operation.

Also in accordance with the instant embodiment of the invention, it is proposed to advance the parts 20 and 21 20 of the record strips differentially. There will accordingly be a difference in spacing between the notches on the disc 123 of the one motorized unit as compared with the spacing between notches on the corresponding disc of the other unit. Should no differential feeding of parts of the strips be required, both parts of the strip could be attached to or engaged by a corresponding pair of feeding devices, with the other pair of feeding devices made ineffective by temporarily disabling the associated motorized unit. In this connection, and as shown in Fig. 13, there is associated with each electromagnet 128 an individual disabling switch 144. The elements 145 and 146, 25 in the diagram of Fig. 13, represent safety switches of various kinds.

Turning now to a consideration of the means for shifting the feeding devices laterally for plural column listing, 30 as seen in Figs. 6 and 14 the shafts 43 and 44 are interconnected by a shift member 147 which connects the shafts 43 and 44 for unison motion in a lateral sense but permits relative rotation thereof. One end of the member 147 is connected by a link 148 to an arm 149 on a 35 shaft 151. The latter extends in a direction parallel to the longitudinal axis of the machine from the rear thereof to the front and at its far end is connected to another lever or arm 152. The lever 152 is connected by a link 153 to another shift member 154 which is constructed and arranged like the member 147 and serves to interconnect the shafts 48 and 51 in the same manner that member 147 interconnects shafts 43 and 44. It is thus seen that the several shafts 43, 44, 48 and 51 are so interconnected that motion of one set of shafts in a lateral 40 sense is partaken of by the other set of shafts, with the motion of both pairs of shafts being in the same direction.

The described lateral motion of the feed shaft is accomplished from the aforesaid clutch shaft 143. This shaft 55 has on it a gear 155. Meshing with the gear 155 is a gear 156 on one end of a cylindrical body 157 formed with a circumferential cam groove 158. An actuating lever 159 is pivoted intermediate its ends at 161 and carries at its one end a pin 162 received in the groove 158. In response to rotation of the body 157, the lever 159 is moved 60 in an oscillatory sense as the pin 162 follows the groove 158. The groove 158, in the present instance, is so formed as to cause the lever 159 to move in one direction during one revolution of the shaft 143 and then to return 65 in the opposite direction during the next succeeding revolution of the shaft 143.

The opposite end of the lever 159 has an elongated slot 163 therein receiving a vertical pin 164. The pin 164 is interconnected by a link 165 with the similar pin 166 set 70 in the shift link 147. As will be understood, the described oscillatory motion of the lever 159 is effective through the link 165 to move the shift members 147 and 154 bodily in a lateral sense.

An adjustable clamp 167 is mounted on the lever 159, 75 in a position overlying the slot 163. The member 167

may be adjusted to vary the position of the pin 164 with respect to lever 159 to thereby vary the degree or amount of movement of the shift lever 147.

The air cylinders 69 (Fig. 6) serve a purpose in damping the lateral shifting motion of the feed shaft. Also assisting in this function is a dash pot 169 (Figs. 3 and 14), the cylinder of which is fastened to the frame and the piston of which is connected to link 153.

The pin wheels 47 and 49 at the front of the machine are interconnected by tie members 171. Pivotaly adjustable on the tie members 171 are side arms 172 carrying a deflector roller 173 which directs one part of the strip out of the path of the other.

It is thought that the operation of the strip feeding apparatus will be largely self evident from the foregoing description. Briefly, however, one cycle of addressograph machine operation will find the record strip assembly extending through the printing zone 37 (Fig. 4) with the stub 23 of a check form in printing position. As this cycle of operation is completed and the stub 23 imprinted, at the start of the next succeeding operation, the shifting lever 159 is actuated to move the feeding devices laterally whereby to move the stub 23 out of printing position and to move the check form proper 22 into printing position. The imprint, occurring near the end of the cycle, accordingly is made upon the check 22. Now as the machine enters a following cycle the record strip assembly is advanced in a longitudinal sense, and, at the same time, the shifting lever 159 moves in a reverse direction to that previously effected and moves the feeding devices back to their original position. The close of this cycle accordingly finds the check stub of the next succeeding record form in imprinting position, and the imprinting feeding and shifting operations continue as above. The longitudinal feeding of the record strip assembly occurs, as before noted, on every other cycle of operation. Further, the strip parts 20 and 21 are fed different amounts, it being unnecessary with respect to the summary strip 27 to allow space for a heading or other material which may appear in the check forms. It will be understood that the method and apparatus of the present invention is applicable generally to plural column listing and is not limited to work upon record forms of any particular kind or use.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A method of advancing continuous manifold strip stationery for plural column listing, including the steps of effecting alternating lateral motions of the entire manifold strip, and on certain only lateral motions thereof advancing a part of the manifold strip one distance in a longitudinal sense and advancing another part of the manifold strip another distance in a longitudinal sense.

2. Apparatus for advancing continuous strip stationery for plural column listing, including strip feeding and supporting means over which said strip is disposed, a power source, a connection from said power source to said means effecting successive lateral adjustment of said means, and another connection from said power source operating said means for strip feeding in a longitudinal

sense in accompaniment only with every other lateral motion of said means.

3. Apparatus for advancing continuous strip stationery for plural column listing, including rotary strip feeding devices having a positive engagement with the strip, a power source a connection from said power source to said devices operable intermittently to rotate said devices for longitudinal advancement of the strip, and another connection from said power source operable intermittently to shift said devices in a lateral sense and in a frequency differing in predetermined extent from the frequency longitudinal advance of the strip.

4. Apparatus for advancing continuous manifold strip stationery for plural column listing, including first strip feeding and supporting devices engaging a part of the manifold strip, second strip feeding and supporting devices engaging another part of the manifold strip, means for effecting unitary lateral adjustments of said devices, and other means for effecting operation of said devices to advance said parts of the strip in a longitudinal sense and independently of one another.

5. Apparatus according to claim 4, characterized in that said other means is operable to advance said one part of the manifold strip longitudinal increments of one distance and is operable to advance said other part of the manifold strip longitudinal increments of another distance.

6. Apparatus for advancing continuous manifold strip stationery for plural column listing, including first and second strip feeding and supporting devices engaging respective parts of said manifold strip, means inter-connecting said devices for relative rotary and unison bodily shifting motions, a power source, means operated from said power source for intermittently shifting said devices in a lateral sense through said interconnecting means, and other means operated from said power source for intermittently operating said devices for advance of said parts of the strip in a longitudinal sense.

7. Apparatus according to claim 6, characterized in that said other means are independently operated whereby said parts of the strip may be advanced differing amounts.

8. Apparatus for advancing continuous manifold strip stationery for plural column listing, including a stationery support, manifold supply racks on said support each holding strip elements, rotary feeding devices arranged in groups in spaced apart relation on said support, each device of each of said groups cooperating with a corresponding device in each other group to engage and control the movements of a respective strip element, said devices being arranged to present said strip elements in superposed relation over said support, said devices being arranged for lateral shifting adjustment relatively to said support, means for effecting unitary lateral adjustment of said devices, and other means for independently rotating sets of corresponding devices.

9. Apparatus for advancing continuous manifold strip stationery for plural column listing, including dual feed mechanisms arranged to feed strip material in superposed adjacent relation to one another, each said mechanism including shaft means arranged for rotary and axial shifting motions, a power source including means performing successive machine cycles, means common to said feed mechanisms for shifting said shaft means laterally during each machine cycle, and other means individual to said feed mechanisms for rotating said shaft means during selected machine cycles.

10. Strip feeding apparatus, including longitudinally spaced apart strip feeding devices, each of said devices including a shaft arranged for rotary and axial motions, sleeves receiving corresponding ends of said shafts, said shafts being connected to said sleeves for unison rotary and relative axial motions, individual power means for said feeding devices, positive driving connections from said power means to respective sleeves rotating said sleeves, other power means, and a common connection

from said other power means to said shafts for moving said shafts axially.

11. Strip feeding apparatus according to claim 10, characterized by control means for operating said individual power means in timed relation to the operation of said other power means. 5
